UNITED STATES PATENT OFFICE.

FREDERICK CHARLES BOHRI, OF LOS ANGELES, CALIFORNIA.

WASHBOARD CLAMP.

1,427,434.

Specification of Letters Patent. Patented Aug. 29, 1922.

Application filed June 16, 1921. Serial No. 478,118.

To all whom it may concern:

Be it known that I, FREDERICK CHARLES BOHRI, a citizen of the United States, residing at Los Angeles, in the county of 5 Los Angeles and State of California, have invented certain new and useful Improvements in Washboard Clamps; and I do declare the following to be a full, clear, and exact description of the invention, such as 10 will enable others skilled in the art to which it appertains, to make and use the same.

This invention relates to an improved clamp which is especially designed for holding a wash-board in an immovable position 15 in a wash-tub to prevent the person doing the work from leaning over onto the board and holding it against unnecessary movement in this way as is usually done.

The principal object of the invention is 20 to generally improve upon the devices of this class by the provision of one of extreme simplicity and durability which is such in construction that it permits the board to be positioned at numerous angles 25 and effectively holds it in any of such positions.

Other features and advantages of the invention will become apparent during the course of the following description.

30 In the accompanying drawings forming a part of this specification and in which like numerals are employed to designate like parts throughout the same:

Figure 1 is an elevational view of one of 35 the clamps showing the same in use.

Figure 2 is a sectional view taken substantially on the plane of the line 2—2 of Fig. 1.

Figure 3 is an enlarged side elevational 40 view of one of the clamps detached from the board and tub.

Figure 4 is a sectional view taken substantially on the plane of the line 4—4 of Fig. 3.

Referring to the drawings, the letter A 45 designates a stationary wash-tub. B designates a conventional type of wash-board and C designates the side bars or legs of the board.

My improved clamp comprises a substantially U-shaped body or yoke 1, one of the arms of which is provided with a lateral projection 2 formed with a screw-threaded hole. The other arm carries an integral

lateral projection which may be conveniently termed a jaw, since it is designed to 55 engage one of the side pieces C of the wash-board. Extending through the screw-threaded hole is a thumb-screw 4 which is disposed at substantially right angles to the arms of the yokes. On the inner end 60 of this screw is a swivelled head 5 which is designed for engagement with the outer face of the tub A as indicated in Fig. 1.

In use, two clamps are used and one is 65 placed adjacent one of the side pieces of the wash-board as shown and the arms thereof permitted to straddle the upper edge of the tub so that the swivelled head 5 of the thumb-screw can be engaged with the 70 tub. After the screws are tightened sufficiently, the jaws 3 are brought tightly 75 against the legs of the board and the latter is clamped in a substantially immovable position in the tub. This being the case, it will be unnecessary to lean on the upper 80 edge of the board in the usual way to hold it against movement. As before indicated, the construction of the clamp which I employ permits the board to be disposed at numerous angles and the board when adjusted as shown in Fig. 1 does not take up 85 much space in the tub.

By carefully considering the description in connection with the drawings, persons familiar with devices of this class will 85 doubtless be able to obtain a clear understanding of the same. In view of this a more lengthy and detailed description is thought unnecessary.

I claim:

A wash board clamp comprising a substantially U-shaped yoke, the arms of which are intended to straddle the side of a tub or the like, the inner arm having an integral laterally disposed jaw at its lower end designed to engage one of the side-pieces of the board, the remaining arm having a projection on its lower end extending in the same direction and in parallelism with said jaw, and a binding screw extending through 95 said projection for engagement with the tub.

In testimony whereof I have hereunto set my hand.

FREDERICK CHARLES BOHRI.
